UNITED STATES PATENT OFFICE.

DICK HUBERT CHESTER, OF BUFFALO, NEW YORK.

HEAT EXCHANGER.

Application filed April 28, 1921. Serial No. 465,110.

To all whom it may concern:

Be it known that I, DICK HUBERT CHESTER, a citizen of the United States, residing in Buffalo, in the county of Erie and State of New York, have invented certain new and useful Improvements in Heat Exchangers, of which the following is a specification.

This invention relates to a heat exchanger designed for the transfer of heat from one liquid to another liquid. It operates on the counter-current principle, in which hot and cold liquids are flowing in opposite directions at all times. One of the liquids passes through tubes, and the other liquid circulates 10 outside of the tubes through conduits, which enclose or encase the tubes. For use for heating oil or water the tubes preferably are straight seamless drawn copper, but tubes of brass, steel, or other metal may be used as 15 may best suit the conditions.

One feature of the invention is that these tubes are expanded or otherwise suitably secured at one end in a stationary tube-sheet while their other ends are secured in a tube-25 sheet forming part of a floating head. This arrangement takes care of the expansion and contraction of the tubes.

Caps or covers are provided for the ends of the outer casings and also for the floating heads.

Another feature of the invention is its accessibility. By removing the caps at each end, the tubes of any section, and the outer conduits as well, are accessible for examination, cleaning or repair.

Another feature is the means for supporting the tubes in separated or spaced relation to each other such as plates each of which is a segment of substantially one-half the 40 cross-sectional area of the conduit.

Another feature appertains to the tube-plate, later described, which in the present instance is a portion of a floating or of a stationary tube-head, as the case may be, and the location and peculiar coactive relations and functions thereof, whereby this plate, in addition to carrying in supporting connection the ends of two sets of tubes, constitutes an impact-plate against which the heating current is turned in a direction transverse to its former line of flow, in the present instance downwardly. By this means said heating current impinges forcibly against the inner surface of said plate, and thereby normally intensifies the heating of this plate, and at the same time causes a circular

stream action or inter-flow of the component portions of the stream, so that those portions intermix and thus further intensify the process of heat transference to and through 60 said plate.

Another feature is that the size of the apparatus, that is, as to the number of related and cooperating sections, is unlimited, as sections can be added so long as the friction 65 does not become so excessive as to reduce unduly the capacity.

In the accompanying drawings which form part of this specification, Figure 1, is a side elevation of the apparatus partly broken 70 away.

Figure 2, is an end elevation as seen from the left hand in Fig. 1.

Fig. 3, is a right end elevation of Fig. 1, a cap or cover being removed and exposing 75 the adjacent tube-plate and tubes.

Fig. 4, is a fragmentary view on the line 4-4 of Fig. 1, as seen from the left hand in Fig. 1.

Fig. 5, is a fragmentary view on the line 80 5-5 of Fig. 1, looking in the direction of the left hand section-line arrow.

Fig. 6, is a fragmentary view on the line 6-6 of Fig. 3 looking in the direction of the 85 section-line arrow.

Similar reference characters refer to similar parts throughout the several views.

My invention comprises in its main parts or elements the supports A, the conduits B, the outer covers C and C'; the intermediate supports D, the tubes E having the stationary plates F, the floating heads G, and their covers H.

The conduits B are of suitable metal, and are in diameter sufficient to receive therein the tubes E with space for circulation of fluid or liquid around said tubes.

The conduits B, are shown in the present instance, as consisting of separate tubular members, arranged in series, parallel to each other and one above the other, resting upon the supports A and spaced apart by the intermediate supports D.

Referring to Fig. 1, each conduit B is a straight portion 10 provided with an exterior annular flange, 11 and 12, at each end.

The first conduit B in the series is provided with a terminal connecting member 13, having a communication means 14, which, in the present instance, is an inlet for the 110 heating medium. The connecting member 13 is provided at each end with an exterior

annular flange such as 15 and 16, the flange 15 being separably secured by bolts or other suitable means, not shown, to the flange 12 of the conduit B. A communication means 5 17, which, in the present instance, provides an outlet for the liquid or fluid which is to be heated, is provided adjacent to the connecting member 13, having an exterior annular flange 18 separably secured by bolts 10 or other suitable means, not shown, to the flange 16 of the connecting member 13, a stationary tube plate F' for the pipes E being separably secured between the flanges 16 and 18; and it should be understood that 15 if desirable in practice, what in the present instance is shown as an inlet may be used as an outlet, and what is shown as an outlet may be used as an inlet.

The conduits B are provided at one end 20 with coupling members 19. Each coupling member 19 comprises two short conduit portions 20 having exterior annular flanges 21, an enlarged portion 22 having an exterior annular flange 23, a straight connecting portion 24 between the portions 19 and a cap C, the enlarged portion 22, the straight connecting portion 24 and the interior of the adjacent cap or cover C providing a passageway for liquid or fluid from one conduit 25 to the other. The flange 21 of the upper portion 20 is separably attached by bolts or other suitable means, not shown, to the flange 11 of the straight length 10 of one conduit B, and the flange 21 of the lower portion 20 is similarly secured to the straight length 10 of the next adjacent conduit B.

Any suitable connections may be used to connect the other end of the conduits in series. When the conduits consist of separate tubular members, then there are preferably used connections such as the coupling members 27 which with the coupling members 19 connect the conduits B in series.

Each coupling member 27 comprises two 45 short conduit portions 28 and a straight connecting portion 29 between the portions 28. The outer end of the member 27 has an exterior annular flange 31, which is separably secured to the flange 26 of the cover C', a 50 stationary tube plate F being separably secured between the flanges 26 and 31. The short portions 28 are each provided with an exterior annular flange 32 which is separably secured to the flanges 12 of the intermediate 55 conduits B, the plate F between the straight connecting portion 29 and the interior of the cover C' providing passageways for liquid or fluid between one conduit and the other. The covers C and C' are preferably of the 60 form shown in the drawings, that is, they are elongated dome-shaped members, the covers C' differing from the covers C only in having an interior of less depth. The covers C are provided with an exterior annular flange 25 which is separably secured

by bolts or other suitable means, not shown, to the flange 23 of the extended portion of the coupling member 19.

The tubes E preferably are of seamless drawn copper, brass or steel, expanded or otherwise secured at one end in stationary tube plates F or F' and similarly secured at the opposite end in a tube plate 36 of the floating head G. The tube plates F' are shorter than the tube plates F, and provide stationary attachment means for a single bank of tubes, and are used for the tubes located in the first and last of the conduits B, while the tube plates F provide stationary attachment means for intermediate tubes, only one instance thereof being shown in the drawings.

The plate F having a straight portion 33, serves as one end support for the tubes or conduits, being fixed between the flanges 26 and 31 to prevent relative movement thereof. This plate with its cover C' forms a passage for fluid between the tubes of two adjacent conduits. The passageway between the plate 33 and the wall of the connecting portion 29 serves to allow the passage of the heating fluid from one conduit B into the next conduit in the same series. The tube plates 36 are separably secured at each end to the exterior flanges 34 of the caps H, 95 which are enclosed by the caps C forming floating heads, there being space, as at 35, between the tube heads G and the covers C whereby provision is made for the expansion and contraction of the tubes E.

For keeping the tubes E spaced apart or separated from each other, the supporting plates 37 and 38 are provided, there being two of such plates shown. Each of these plates is substantially a segment of one-half the cross-sectional area of the conduit B, mounted on the tubes E and slightly spaced from the conduit B to permit the plates freely to slide along the conduit B to allow for expansion and contraction of the tubes E relative to the conduit B. The plates 37 and 38 are spaced apart longitudinally, the plate 37 being located in the lower part of the conduit B, while the plate 38 is in the upper part, the tubes E passing through the plates. The current of the fluid flowing through the conduit B on the exterior of the tube E passes over one plate as at 39, and under the other plate, as at 40, without material interruption of the flow.

To afford means for transverse communication between the tubes E of one series of tubes and the tubes E of an adjacent series the cross-connections J, Figs. 3 and 6, are provided, these cross-connections being 125 of separably connected parts. Cross-connections for transverse communication between the conduits B are shown in Figs. 1 and 6 and are denoted by J'.

In practice the parts comprising the inven-

tion may be provided with an exterior covering, not shown, of asbestos or other suitable material for preventing loss of heat by radiation, or a suitable heat case or enclosing means, not shown, for the whole structure may be provided.

5 In operation: The heating fluid is introduced into the exchanger at the inlet 14 appurtenant to the first of the series of pipes or conduits B, and flows through the series of pipes or conduits and through the passageways and cross-connections around or exteriorly of the tubes E in the direction indicated by the arrows, and is discharged by 10 the outlet 14 appurtenant to the last of the pipes or conduits in the series. The fluid or liquid to be heated is introduced at the inlet 17 appurtenant to the tubes E of the last pipe or conduit of the series, the flow 15 being in the direction indicated by the arrows and counter to the direction of flow of the heating fluid or liquid, the fluid or liquid to be heated being discharged by the outlet 17 appurtenant to the tubes E of the 20 first pipe or conduit of the series.

In the course of the flow from an overlying conduit B to an underlying conduit B through the passageways provided by the coupling members 19 and 27, the heating 25 fluid or liquid is forcibly impinged against the interior surface of the plate 36 of a floating tube head G, or against the interior surface of the plate as the case may be, and is turned substantially at right angles or 30 transversely to the direction of former flow, and is caused to flow through the underlying conduit B reversely to the flow through the overlying conduit B.

Having thus described my invention, it 35 should be understood that there may be modifications thereof and variations therein

without departing from the spirit of the invention, or exceeding the scope of the appended claims.

I claim:

1. The combination with a plurality of cylindrical conduits arranged parallel to one another of a plurality of tubes parallelly disposed in each of said conduits, coupling members connecting said cylindrical conduits in series, and floating heads in alternate coupling members providing communication between the tubes in one conduit and the tubes in the connected conduit and providing for expansion and contraction of the 50 tubes and conduits.

2. The combination with a plurality of cylindrical conduits arranged parallel to one another, of a plurality of tubes parallelly disposed in each of said conduits, coupling members connecting said cylindrical conduits, in series, partitions in alternate coupling members separating the passageways of said tubes from the passageways surrounding the tubes, and floating heads in the 60 remaining coupling members affording communication between the successive sets of tubes and providing for expansion and contraction of the tubes.

3. The combination with a plurality of 65 conduits arranged parallel to one another, of a plurality of tubes parallelly disposed in each of said conduits, baffle plates floatingly disposed in said conduits and having openings for the passage of the tubes therethrough, connections connecting said conduits in series, partitions in alternate connections separating the passageways of said tubes from the passageways surrounding the tubes, and floating heads in the remaining 70 connections.

D. HUBERT CHESTER.
